MATERIAL WORKING APPARATUS

Martin J. Seagren, Chicago, Ill., assignor to
Western Electric Company, Incorporated, New
York, N. Y., a corporation of New York

Application July 9, 1937, Serial No. 152,735

1 Claim. (Cl. 164—59)

This invention relates to material working apparatus, and more particularly to material stop devices for material working apparatus, such as punching and shearing presses.

5 An object of this invention is to provide an effective and simple material stop device capable of yielding when the material being worked close to its edge, abutting the stop device, bulges, thus preventing the misalignment of the cooperating 10 working tools and consequent damage thereto.

In accordance with one embodiment of this invention as used in connection with a material punching apparatus employing a reciprocative punch and cooperating stationary die member 15 for working heavy stock or parts, there is provided a spring pressed stop device for positioning the forward edge of the stock, the stop device being capable of yielding as the material of the stock bulges when being worked close to its edge 20 abutting the stop device, the movement of the stop device preventing the forcing or bending of the punch out of register with its die and subsequent breakage thereof. The spring pressed stop device may also serve as an ejector for the worked 25 part from the apparatus as the punch is retracted.

Other objects and advantages of this invention will more fully appear from the following detailed description, taken in connection with the accompanying drawing, wherein

30 Fig. 1 is a diagrammatic fragmentary elevational view, partly in section, of a material working apparatus comprising a reciprocative punch and cooperating stationary die showing the yieldable material stop device embodying the invention applied thereto, and

35 Fig. 2 is a plan view thereof with the movable punch removed.

Referring now to the drawing, the stop device embodying the features of this invention has been 40 shown, for example, applied to a metal strip or part perforating machine which may be of any suitable type, for instance, a punch press. Since it is not essential to a complete understanding of the invention, the machine has not been illustrated, except those parts directly concerned with the invention, which comprise the following:

A vertical reciprocative platen 10 carrying a 45 perforating punch 11 and a cooperating stationary die bed 12, the die bed 11, having an opening 14 which is of similar shape to that of the material to be punched or sheared from a metal strip or part indicated at 17. The punch 11 which also conforms to that of the material to be sheared from the part 17 is shaped to suitably fit in the die opening 14 whereby in a down-

ward movement of the press platen 10 to the position shown in the drawing the part 17 will be perforated, the portion which has been punched or sheared from the part being indicated at 18. Fixed in a suitable manner (not shown) to the upper surface of the die bed 12 is a stripper plate 19 formed with a channel 20 in its bottom surface serving to guide the strip or part 17 on the die bed 12 into position under the punch 11 which is in an elevated position at this time. An aperture 21 is provided in the stripper plate 19 for the free passage therethrough of the punch 11 during its reciprocation. In an upward movement of the punch 11 after its operation on the part 17, it will be obvious that the plate 19 will strip the part therefrom.

The stop device embodying the features of this invention for positioning the forward or leading in edge of the part 17 relative to the cooperating punch 11 and die opening 14 and thereby determining the location of the perforation relative to the leading in edge of the part comprises a bar 25 reciprocably carried on a pair of headed pins 26 threaded at their inner ends into the right end of the stripper plate. Surrounding each of the pins 26 between the inner faces of the heads thereof and the outer end of the bar 25 is a compression spring 27 which acts to normally maintain the stop bar 25 in abutting relation with the end of the stripper plate as shown in full lines in the drawing. Although in the present application of the stop bar 25 it has been described and illustrated as being carried on and engaging the stripper plate it will be obvious that it could be otherwise mounted.

In working a metal strip or part, such as 17 of relatively great thickness, close to its forward or leading in edge difficulty is experienced when a rigid stop is used due to the distortion or bulging of the metal between the rigid stop and the punch and die members. The bulging of the metal causes a misalignment of the punch and die members, the punch being forced or bent out of register with the die opening and finally causing the breakage of these parts.

In setting up the apparatus preparatory to working a metal strip or part of a certain thickness with the work being performed a predetermined distance from its forward edge, such thickness and distance having been found by experience to be such that a bulging of the metal between the punch 11 and the stop bar 25 will occur, suitable springs are installed on the headed pins 26 which will permit the bar to yield sufficiently as the bulging of the metal occurs so that 55

no deleterious lateral force is applied to the punch. If no bulging of the metal takes place no movement of the bar stop occurs.

In the operation of the apparatus as the punch 5 11 descends and perforates the part 17 any distortion or bulging of the metal, indicated by the curved broken line 28 (Fig. 2), between the punch and the abutting surfaces of the part being worked and the stop bar 25 causes the bar to 10 yield and it moves outwardly on the pins 26 against the resisting force of the compression springs 27 to the position indicated by the broken lines 29. Thus no appreciable lateral force is exerted on the punch 11 or die bed 12 tending to 15 bend or force them out of register. During the retraction of the punch 11 the perforated part 17 is stripped from the punch by the stripper plate 19 and as the part is freed from the punch the energy stored in the compression springs 27 20 is suddenly released and the resultant movement of the stop bar 25 to its normal stop position abutting the stripper plate serves to eject the worked part 17 from the apparatus.

From the foregoing description it will be apparent that an effective and simple material stop device is provided for material punching apparatus which is capable of yielding upon the material between the cooperating punch and die

members and the stop device being distorted in the manner above described, thus preventing the misalignment and breakage of the punch and die members. Further, that the resilient stop device may also serve as an ejector for the worked material from the apparatus as the punch is retracted.

It will be understood that the embodiment herein described is merely illustrative of the invention and one application thereof, the invention being limited only by the scope of the appended claim.

What is claimed is:

In an apparatus for working heavy metal stock or parts close to an edge thereof, a reciprocative punch, a cooperating die member aligned with the punch, and a stop device for the part against which the same is abutted in positioning the part to be worked comprising a reciprocably mounted bar, an abutment for maintaining said bar in a predetermined stop position, and resilient means effective to constantly urge said bar against said abutment but permitting the bar to move along a rectilinear line solely in response to a bulging of the part at said edge thereof during the working of the part to prevent deformation of the punch.

MARTIN J. SEAGREN.
